DESIGN FOR A DISH OR SIMILAR ARTICLE

Maurice Exelmans, Paris, France, assignor to Verlys of America, Inc., New York, N. Y., a corporation of New York

Application September 13, 1938, Serial No. 79,866

Term of patent 7 years

To all whom it may concern:

Be it known that I, Maurice Exelmans, a citizen of the Republic of France and a resident of Paris, France, have invented a new, original, and ornamental Design for a Dish or Similar Article, of which the following is a specification, reference being had to the accompanying drawing, forming a part thereof.

Figure 1 is a top plan view of the dish or similar article, showing my new design, and Figure 2 is a side elevational view thereof.

I claim:

The ornamental design for a dish or similar article, as shown.
